US00D496355S1

(12) **United States Design Patent** (10) Patent No.: **US D496,355 S**
Harshbarger et al. (45) Date of Patent: **** Sep. 21, 2004**

(54) **PORTION OF A HOUSING FOR A COMMUNICATION DEVICE**

(75) Inventors: **Michael Harshbarger**, Lake Villa, IL (US); **Shakil Barkat**, Hawthorn Woods, IL (US); **Phillips W. Lohr**, Deerfield, IL (US)

(73) Assignee: **Motorola, Inc.**, Schaumburg, IL (US)

(**) Term: **14 Years**

(21) Appl. No.: **29/177,510**

(22) Filed: **Mar. 10, 2003**

(51) LOC (7) Cl. **14-03**

(52) U.S. Cl. **D14/248**; D16/208

(57) **CLAIM**

The ornamental design for a portion of a housing for a communication device, as shown and described.

DESCRIPTION

FIG. 1 is a perspective view of an ornamental design of one embodiment of a portion of a housing for a communication device showing our new design.

FIG. 2 is a right side orthographic view thereof.

FIG. 3 is a bottom orthographic view thereof.

FIG. 4 is a top orthographic view thereof.

FIG. 5 is a left side orthographic view thereof; and,

FIG. 6 is a front orthographic view thereof.

The broken lines shown in FIGS. 1-6 are included for the purpose of illustrating environmental elements only and form no part of the claimed design.
